UNITED STATES PATENT OFFICE.

JOSEPH W. WEISS AND THOMAS G. DEWLING, OF BALTIMORE, MARYLAND.

SCORING AND CUTTING MACHINE.

1,143,672.

Specification of Letters Patent. Patented June 22, 1915.

Application filed July 9, 1914. Serial No. 849,883.

To all whom it may concern:

Be it known that we, JOSEPH W. WEISS and THOMAS G. DEWLING, citizens of the United States of America, residing at city 5 of Baltimore, State of Maryland, have invented certain new and useful Improvements in Scoring and Cutting Machines, of which the following is a specification.

This invention relates to a machine for 10 cutting and scoring box blanks in the manufacture of boxes in accordance with U. S. Patent No. 1,063,845, dated June 3rd, 1913.

The box referred to is a new article of manufacture and the machine which is the 15 subject of this invention is constructed for the purpose of producing the blanks from which this box is manufactured, though certain of the features of the machine are capable of a broader use within the scope of our 20 invention.

The box illustrated in the patent is reinforced by means of plaits or folds extending along the corners, and while all the corners of the box may be thus reinforced, in the 25 preferred form of the invention, the plaits extend along the top and bottom corners or horizontal edges only, and the machine of the present invention is designed with a particular view to its use in the manufacture 30 of such a box.

The principal difficulty heretofore encountered in the manufacture of boxes in accordance with the machine of the patent, relates to the bending or scoring of the 35 plaited portions of the paper at the corners. Where the paper is thus thickened by plaiting, the outside fibers give way and the plaits break at the corners. By the use of this machine, the corners are scored and the 40 top and bottom flaps are cut at a single operation, and particularly, the plaited portions are so manipulated in scoring that the strain is removed from the outside fibers and the corners are formed without breaking or 45 even weakening the material to any considerable extent.

Although the device and the features thereof may be otherwise arranged within the scope of the invention, in the form illustrated, the machine consists of a vertically reciprocating carriage and a stationary table, the upper or moving member is provided with two knives for cutting the top

and bottom flaps, two plait scorers, the construction of which is an important feature 55 of this invention, and a corner scoring device which may be of any preferred construction or may even be made like the plait scorer without departure from the spirit of the invention. These elements are placed in 60 a line preferably at right angles to the direction of presentation of the material, *i. e.*, transversely of the machine, the cutters being at the outside, the plait scorers or dies next and the corner scorer for scoring the 65 material between the plaits, in the center. This latter is not an important feature and may be widely varied or omitted within the scope of our invention. On the table are coöperating members correspondingly 70 placed. These consist of two knife slots, one at each side and suitable internal formers for the corners.

The knives are of a peculiar construction. They cut the material to form the flaps in 75 the same operation the corners are formed. At this time the paper is bent upward toward the knives and the tendency is to crush and jam the edges against the knife after cutting, and break the paper away at the 80 corners. To avoid this, the knives are constructed with a particular view to overcoming these difficulties, as hereinafter described.

As we have already pointed out, the plait 85 scorer or die which is the term which we have applied to the device for forming the corners at the plaited portions, is an important feature of our invention, and while the general principles upon which it is constructed, are not broadly new, it differs in 90 certain important points from the device of the prior art and it is by virtue of these features that the operation referred to, *i. e.*, the scoring of the plaited reinforce, is ac- 95 complished without breaking the material, for various attempts have been made to apply the devices of the prior art to this end and none of these attempts have been suc- 100 cessful, while the present structure is an un- qualified success.

The prior structure referred to consists of a die having a central block mounted to move vertically and two fingers or pushers pivoted at the side, swinging inward and 105 resting on this block. These are rounded

and roughened on their lower inner edges to engage the paper, the intended operation being as follows: The die is pressed against the paper over a suitable frame or edge and as the ends of the fingers are forced downward, they swing to a horizontal position tending to force the top layers of the material inward toward the bend and take the strain off the outside fibers. The central block engages the material and yields upwardly as the arms swing. However, this device, while seemingly right as to the theory, has not proved a success in its operation upon the plaited material, which is used in manufacturing the patented box referred to, as the breaking of the outside fibers is not prevented.

As a substitute for the old structure and to overcome the difficulties named, we have constructed a die having the gathering fingers described, but we eliminate the central yielding block and permit the paper instead to bear against the solid portion of the die block or frame. At each side of the center, we place sliding members referred to herein as knuckles. These are mounted to slide vertically and are provided with springs which tend to hold them in the bottom position. They are spaced apart by a distance equal to the width of the corner to be formed, the inner surfaces of the knuckles being preferably inclined at an angle shown as substantially 45 degrees to the horizontal. The ends of the gathering fingers on these knuckles yield as the die is pressed down on the material over the corner former, against which it is later pressed by the rigid central portion of the die block, and the fingers in swinging upward gather the material and force it in toward the corner relieving the tension at this point so that breakage is always prevented and the corner is formed in the plaited reinforce without materially weakening the folded or plaited paper.

In the accompanying drawings, we have illustrated a machine embodying our invention in its preferred form.

In these drawings, Figure 1 is a front elevation, Fig. 2 is a rear elevation, Fig. 3 is a top plan divided on a central longitudinal plane, the top of the left half of the machine above the line 3, 3 of Fig. 1 being removed to show the table, etc., Fig. 4 is a side elevation of the entire machine on a reduced scale, Fig. 5 is a side elevation of the plait die, Fig. 6 is a front or rear elevation of the same, Fig. 7 is a section on the line 7, 7 of Fig. 3, Fig. 8 is a view showing the die and former operating on the plait, and Fig. 9 is an edge elevation of the knife.

Referring to the drawings by numerals, each of which is used to indicate the same or similar parts in the different figures, the machine, which may be broadly termed a

press, consists of a frame 1 having a table 2 which, when the machine is set up, is extended to the front and rear as shown in Fig. 4. The press is provided with a reciprocating carriage 3 mounted on vertical guides 4. These are engaged by followers 5 on the carriage, the latter being held normally in raised position by means of springs 6 shown in the form of spiral springs encircling the rods 4.

The machine is provided with a horizontal shaft 7 extending transversely and driven by any suitable means as the belt 8. On this shaft, in the form of the device illustrated, are eccentrics 9, one near each end of the shaft, the same being engaged by suitable straps 10 on the connecting rods 11 and being pivotally connected to the carriage at 12 whereby the latter is given a reciprocating motion in a vertical path at each rotation of the shaft.

The operative parts of the machine, *i. e.*, the elements which act upon the plaited paper, are mounted part of them on the carriage, disposed downwardly, and the coöperating members on the table, all being arranged in a line transverse to the machine, *i. e.*, parallel to the shaft. At the left and right sides, secured to the carriage, are knives 13 for cutting the top and bottom flaps. These preferably have the saw-tooth inclined edge illustrated, with a depending guiding shank 14 at the outer side which extends down through the slot 15 in the table provided for the reception of the knife. The knives cut the material while the corners are being formed and the material is bent or gathered for the purpose of forming the corners. To avoid breaking the edges which are thus forced against the knives as they descend, the knives are given a peculiar formation. They are apertured horizontally at 13', adjacent the dies, the slot or aperture extending a considerable portion of the length of the knife, as shown, where the tendency to crush the paper is greatest.

Further, the knives or cutters are widened at the cutting edge 13'' so as to remove a comparatively wide strip of material, and reduced above to relieve the edges from pressure after the paper is cut. At the inner end of each knife 13 is a die 16 for treating the plaited portions of the blank and forming the corners therein. These coöperate with corresponding internal former members 17 on the table. In the center, between the two dies 16 is a corner scoring device 18 of the usual or any preferred form for treating the corners of the paper between the plaits. This coöperates with an internal corner former 19 on the table.

In the form of the machine shown, the carriage consists of a central beam or lay 20 beveled to engage a corresponding groove 21 in the various tool supports, the beam ex-

tending from side to side of the machine and being reinforced by webs 22 in any suitable form, and carrying the necessary follower members 5 to engage the upright rods or ways 4. Each of the knives 13 is mounted in or on a block 23 having the described groove 21 to receive the beam 20 so that the knife is adjustable transversely of the machine and may be clamped with the block in 13 adjusted position in any suitable manner as by means of thumb screws 24.

In the form of the device shown, the block 23 is provided with an elongated vertical shoulder 25 on its under side, to which 15 the knife is bolted in a convenient manner as shown in Fig. 7. Of the dies 16, one is, as we have stated, mounted at the inner end of each of the cutters 13, and in the present instance, to this end, each of the die blocks is 20 notched as at 26 in Fig. 5 to engage or interlock with the corresponding knife block 23. However, the die may be otherwise mounted and provided with a separate supporting block to engage the ways 20 within 25 the scope of our invention, the structure shown being particularly convenient because the dies 16 are in this instance intended to operate on the plaits which are at the top and bottom edges of the box and the cuts for 30 the formation of the flaps extend downward to the plaits so that the cuts terminate where the scores formed by the dies 16 begin, and the tools which perform these respective operations are necessarily placed in juxtaposition and if adjustment is to take place, both 35 members are most conveniently adjusted together toward and from the center of the machine for the formation of boxes of correspondingly varying height, the feed or 40 feed gages being varied in position to determine the width of the box, *i. e.*, the distance between the scores and cuts, in a direction at right angles to the line upon which they are formed. The corner scorer 18 be- 45 tween the dies 16, is supported upon a suitable block 30, adjustable along the lay or beam 20 of the carriage, and may be widely varied or even dispensed with within the 50 scope of the invention. To make different sized boxes, scorers of different lengths are of course used.

The table 2, as shown, is formed in two sections supported upon a beam or way 31 formed on the frame of the machine, the 55 table sections being correspondingly grooved to engage the ways. These table sections are held in adjusted position by means of bolts 32 and are slotted to admit the knife and grooved at 34 to receive the edge plates 58 with the slot 15, and the formers 17 and 19, the latter being so placed that they 60 bridge the space between the table sections. Referring particularly to the dies 16 for scoring the plaited edges of the boxes, in 65 the form of the invention shown, these con-

sist of a block, frame or body member 36 having ways 37 for the sliding knuckles 38 mounted on shanks 39 seated in corresponding apertures in the block, the shanks being held against actual withdrawal from the 70 blocks by means of heads 40. Spiral springs 41 within the ways tend to maintain the knuckles normally in advanced position. Pivotally mounted on the sides of the block 36 are gathering fingers 42. These are 75 rounded and roughened at 43 at their lower and inner ends and provided with stops 44' which are engaged by abutments 44, to prevent the arms from swinging downward to vertical position. The arms, near the end 80 portions thereof, rest on the bottom faces of the knuckles 38.

In Figs. 5 and 8 in connection with the die 16, we have shown a section of the co-operating internal former 17. This consists 85 of an upright rib 50 of a width slightly less than the distance between the knuckles 38, the rib 50 having its longitudinal corners provided with supplemental ribs 51. In Fig. 8, the former and die are shown in 90 connection with a piece of plaited paper 53, the position of the parts and the material being that which they take at the end of the stroke. It will be noted that the ends 43 of the fingers engage the paper some dis- 95 tance from the former, and as the die de-scends, till the block presses the paper against the former, the fingers, swinging up-ward and inward, gather the paper and draw it inward toward the bend so that the 100 scoring of the thickened material is ac-complished without putting undue tension on the outside fibers and thus breaking the material from the outer face of the bend.

The operation will be apparent from the 105 preamble and description taken in connection with the drawings. The paper is pre-sented to the machine in the form of plaited strips of the length required to make a single box, the plaits being preferably longitu-dinal, spaced apart by a distance equal to the 110 height of the box and spaced from the lateral edges of the length of the flaps, *i. e.*, the width of the box. To position the lateral edge, there is a stop 55, which is adjustable 115 transversely by means of a slot and bolt 56, see Fig. 3. A table 57 extending to the front and rear of the press, as shown in Fig. 4, is preferably provided. This table has stops 58 spaced forward in the direction of the 120 operator, the distances between the stops being equal to the length of the box sides, *i. e.*, the distance by which the cuts and scores are spaced. The manner of operation is apparent. One lateral edge of the sheet 125 of paper is placed against the stop 55 and the rear edge is placed against the most re-mote of the stops 58 and after each cut the paper is advanced and the rear is abutted against the next succeeding stop in the di- 130

rection of the cutters, until the entire ex-
panse of material has been cut and scored.
The cutters, descending upon the material
placed over the slots 15, make a clean cut
separating the flaps in the manner desired.
5 The knives cut the flaps as the corners are
formed. At this time, the paper is bent
upward toward the knives and the natural
tendency is to crush and break the cut edges
10 against the knife as they are forced down-
ward with something resembling a toggle
action, and there is also a tendency to tear
backward from the cut at the corner of the
box. To avoid this, the edge of the knife
15 is thickened so that it removes a considerable
strip of paper and the shank of the knife
toward the dies, where the breaking tend-
ency is greatest, is removed leaving the open-
ing 13'; also the remainder of the knife
20 above the cutting edge 13" is made thin to
free the material after cutting.

The operation of the device for scoring
or bending the plaits has already been de-
scribed. Between the dies 16 is the element
25 18 with the coöperating member 19, though,
as we have stated, this may be omitted within
the scope of the invention. Its function is
to bend the body of the material between the
30 plaits and thus form the corners between the
top and bottom of the box. Any well-known
type of scorer may be used or the paper may
be bent in any preferred manner.

We have thus described specifically and in
35 detail our preferred form of die for use in
forming corners in thick or plaited material
and we have also described a machine of
which this die is an element and in connec-
tion with which it is used in scoring plaited
40 blanks for the formation of boxes. The de-
scription is specific to a degree to the end
that the invention may be understood and
operated by those skilled in the art. How-
ever, the specific terms herein are used in
45 their descriptive rather than in their limit-
ing sense and the scope of the invention is
defined in the claims.

We claim—

1. In a machine for making box blanks,
50 two corner forming plait dies arranged in
alinement in the direction of the length of
the corner being formed and having their
outer edges spaced apart by a distance equal
55 to the height of the box to be formed, the
inner edges being spaced by a corresponding
distance, which is the distance first named
diminished by twice the width of the plait,
corresponding internal corner formers and
60 means for moving the dies simultaneously
toward and from the formers.

60 2. A machine for forming box blanks con-
sisting of a table, a reciprocating carrier, a
pair of flap cutters, a pair of plait dies and
a corner scorer with the corresponding in-
65 ternal formers for the dies and scorer, the
various operative members, *i. e.*, the cutters,

dies and scorer, being mounted in alinement
in the direction of the length of the corner
being formed, the cutters at each end, the
dies one at each side just inside the cutters,
and the scorer in the center.

70

3. In a machine for making box blanks, a
table, a carrier mounted to reciprocate at
right angles to the surface of the table to-
ward and from the table, flap cutting knives
arranged in a vertical plane extending trans-
versely of the table, one at each side de-
pending from and secured to the carrier,
two corner forming plait dies mounted on
the carrier in alinement with the knives, so
that the knives and dies form a single line
80 in the direction of the cuts and corners
formed, one adjacent the inner end of each
knife and spaced well apart, and members
coöperating with the knives and with the
dies, the same being mounted on the table in
85 the path of the corresponding members.

80

4. In a machine for making box blanks, a
table, a carrier mounted to reciprocate at
right angles to the surface of the table to-
ward and from the table, flap cutting knives
arranged in a vertical plane, one at each
90 side depending from and secured to the car-
rier, two corner forming plait dies mounted
on the carrier with their operative surfaces
in alinement with the knives, one adjacent
the inner end of each knife, and members
95 coöperating with the knives and with the
dies, the same being mounted on the table
in the path of the corresponding members,
the outer edges of the dies being spaced
100 apart by a distance equal to the height of
the boxes to be made and the inner edges
being spaced apart by a corresponding dis-
tance.

90

5. In a machine for making box blanks
105 from plaited paper strips, a table, a carrier
mounted to reciprocate at right angles to
the surface of the table toward and from
the table, flap cutting knives arranged in a
vertical plane transversely of the table, one
110 at each side depending from and secured to
the carrier, two corner forming dies mount-
ed on the carrier with their operative sur-
faces in alinement with the knives, one ad-
jacent the inner end of each knife, and mem-
115 bers coöperating with the knives and with
the dies, the same being mounted on the
table in the path of the corresponding mem-
bers, the dies being of a width correspond-
ing to that of the plaits and spaced apart
120 by a distance equal to the distance by which
the plaits are spaced.

115

6. In a machine for making box blanks
125 from plaited paper strips, a table, a carrier
mounted to reciprocate at right angles to the
surface of the table toward and from the
table, flap cutting knives arranged in a ver-
tical plane transversely of the table, one at
130 each side depending from and secured to
the carrier, two corner forming dies mount-

125

130

ed on the carrier with their operative surfaces in alinement with the knives, one adjacent the inner end of each knife, members 5 coöperating with the knives and with the dies, the same being mounted on the table in the path of the corresponding members, the dies being of a width corresponding to that of the plaits and spaced apart by a distance equal to the distance by which the 10 plaits are spaced, and a corner scorer between the dies.

7. In a machine for making box blanks, a corner die consisting of a support gathering fingers thereon pivoted at the sides to swing 15 inward and upward and spring-pressed sliding means upon which the fingers rest, and an abutment between the fingers rigid with the support.

8. In a machine for making box blanks, 20 a corner die having gathering fingers pivoted at the sides to swing inward and upward and sliding knuckles, one for each finger, upon which the fingers rest, and resilient means tending to advance the 25 knuckles, the knuckles being spaced apart by a distance equal to the width of the corner to be formed.

9. Means for forming box corners of thick or plaited paper consisting of a die block 30 and an internal former, the die having gathering fingers pivoted at each side to swing upward and inward, knuckles mounted to slide and provided with springs tending to advance them in the plane of oscillation of 35 the fingers, the knuckles being spaced apart by a distance equal to the width of the corner to be formed, the ends of the fingers resting on the knuckles, and the internal former being of a width slightly less than 40 the distance between the knuckles, the same being placed in the path of the center of the die block between the knuckles.

10. Means for forming box corners of thick or plaited paper consisting of a die 45 block and an internal former, the die having gathering fingers pivoted at each side to swing upward and inward, knuckles mounted to slide and provided with springs tending to advance them in the plane of 50 oscillation of the fingers, the knuckles being spaced apart by a distance equal to the width of the corner to be formed, the ends of the fingers resting on the knuckles, and the internal former being of a width 55 slightly less than the distance between the knuckles, the same being placed in the path of the center of the die block between the knuckles, the center portion of the die block which coöperates with the former being 60 rigid and integral with the block.

11. Means for forming box corners of thick or plaited paper consisting of a die and an internal former, the die having gathering fingers pivoted at each side to 65 swing upward and inward, knuckles mount-

ed to slide and provided with springs tending to advance them in the plane of oscillation of the fingers, the knuckles being spaced apart by a distance equal to the width of the corner to be formed, the ends of the 70 fingers resting on the knuckles, means for preventing downward rotation of the fingers to vertical position, the internal former being of a width slightly less than the distance between the knuckles, the same being 75 placed in the path of the center of the die, the former having ribs on the two opposite edges parallel to the inner surfaces of the knuckles and the corresponding edges of the gathering fingers.

12. In a machine for cutting and scoring box blanks, in combination with a corner die adapted to gather the material and form an upright projecting ridge, a knife having a wide cutting edge, a reduced shank 85 and an aperture in the shank adjacent the die being so placed as to cut the ridged portion of the material longitudinally of the ridge.

13. In a machine for cutting and scoring 90 plaited paper in the formation of boxes, a corner die adapted to gather the material and form an upright projecting ridge and a knife, placed in alinement, the knife having a wide cutting edge and a reduced shank 95 being so placed as to cut the ridged portion of the material longitudinally of the ridge.

14. In a machine for cutting and scoring plaited paper in the formation of boxes, a corner die and a knife placed in alinement, 100 the die being adapted to gather the material and form an upright ridge, the knife having a wide cutting edge and a reduced shank, the shank being apertured adjacent the die and for a considerable portion of its length, 105 the knife being so placed as to cut the ridged portion of the material longitudinally of the ridge.

15. In a machine for making box blanks of plaited material, two corner forming 110 plait dies having their operative edges arranged in alinement to form corner scores in the same line and having their outer edges spaced apart by a distance equal to the height of the box to be formed, the inner 115 edges being spaced apart by a distance equal to the distance between the plaits, corresponding internal corner formers and means for moving the dies toward and from the corners.

16. In a machine for making box blanks, a corner die consisting of a support having gathering fingers pivoted to swing inward and upward, spring-pressed sliding means upon which the fingers rest, and a rigid 125 abutment between the fingers.

17. In a machine for making box blanks, a corner die consisting of a support having gathering fingers pivoted to swing inward and upward, spring-pressed sliding means 130

upon which the fingers rest, a rigid abutment between the fingers, and an internal former, the same being placed in the path of the rigid abutment between the fingers 5 so that when the die is advanced, the rigid portion engages the material where it rests on the former.

Signed by us at city of Baltimore, State of Maryland, this 2nd day of July, 1914.
